(57) **CLAIM**

The ornamental design for an end cap for an air tank, as shown and described.

DESCRIPTION

FIG. 1 is a perspective view of an end cap for an air tank;
FIG. 2 is a front side elevational view thereof;
FIG. 3 is rear side elevational view thereof;
FIG. 4 is a right side elevational view thereof;
FIG. 5 is left side elevational view thereof;
FIG. 6 is a top view thereof; and,
FIG. 7 is a bottom view thereof.

The broken lines depict environmental structure for illustrative purposes only and form no part of the claimed design.
